UNITED STATES PATENT OFFICE.

HENRY P. BALTZER, OF HAMBURG, NEW YORK.

BUCKLE.

Application filed December 18, 1927. Serial No. 239,686.

This invention relates to improvements in buckles, and more particularly to an adjustable buckle for effecting relatively fine or slight adjustment between the parts which the buckle connects.

When buckles of the ordinary, well-known type are used, for example, for connecting two strap ends or other parts, one at least of which is provided with a row of spaced apertures, adjustment of said straps can only be had in accordance with the spacing between said holes. It is necessary at times, however, to provide a relatively fine adjustment between the connected straps or other parts, which would be less than the distance between two adjacent apertures, and could therefore not be effected by changing the buckle from one aperture to another.

The principal object of the present invention is to provide a buckle for connecting two spaced parts, which in addition to permitting a primary adjustment as above described, will also permit a fine adjustment, for example, for any amount less than the distance between two of said apertures, without disturbing the original primary adjustment or relation between the buckle and said apertured part; also to construct an adjustable buckle to be secured on one of said parts to be connected, and which has a frame or member to which the other part is connected; and means for effecting relatively slight movements of said frame member and its attached part towards or from said other part; also to provide an adjustable buckle in which said frame is swivelled to permit relative turning movements between said parts; also to provide an adjustable buckle for the purpose described which is of relatively simple construction and inexpensive to produce and which nevertheless is strong and sturdy, adapted for long use and will not readily get out of order; also to improve the construction of buckles in the other respects hereinafter set forth and claimed.

The buckle of the present invention is particularly adapted for connecting the two strap ends or parts of a truss to be worn about the body, to provide varying fine adjustments from time to time and independently of the primary or approximate initial adjustment made in accordance with the girth of the wearer. The buckle, however, can be used with advantage for many other purposes.

In the accompanying drawings:

Fig. 1 is a face or plan view of two strap

ends or parts, connected by means of a buckle embodying my invention.

Fig. 2 is a side view thereof.

Fig. 3 is a view similar to Fig. 1, with a portion of one of the straps broken away to disclose the underlying parts.

Fig. 4 is a longitudinal section thereof, on line 4—4, Fig. 1, one of the straps being shown in broken lines.

Fig. 5 is a fragmentary side elevation of a part of the buckle, showing the end of a strap being placed into operative relation thereto.

Fig. 6 is a sectional view of a slightly modified form of buckle.

Fig. 7 is a side elevation partly in section, of another modified form of buckle.

In the embodiment of the invention illustrated in Figs. 1—5 of the drawings, the improved buckle 10 is shown as connecting the end portions of two flexible straps or parts 11 and 12. The strap 12 is provided with the usual longitudinal series of spaced holes or apertures 13.

The buckle 10 comprises a fitting or attaching portion 14, of any suitable form adapting it to be secured to the end of the strap 11. In the form illustrated, the fitting is of U-shape, the spaced legs 15 of which extend lengthwise of and straddle said end and are secured thereto, as by rivets or other fastenings 16.

A frame or holding member 18, preferably of rectangular form, is disposed in spaced relation to the fitting 14, and is adapted to receive and hold the apertured end of the other strap 12, which is passed through the opening in said frame and bears against a transverse bar or part 19 thereof. The opposite transverse bar 20 of said frame is connected to the outer end portion of a stem or elongated member 22 carried by and extending from the fitting 14, said stem 22 being preferably arranged in a hole 23 in said bar, and having an enlargement or shoulder 24 against which said bar abuts to hold the frame in position. The free end or portion of the stem 22 which is remote from the fitting 14 or is disposed outwardly beyond the shoulder 24, is preferably made in the form of a prong 25, which constitutes the tongue of the buckle. This prong is adapted, when the strap 12 is passed through the frame 18, to enter any one of the holes 13 in said strap for holding the strap in desired relation to said frame in the usual manner, thus providing a coarse or approximate adjustment for varying the rela-

tion of the straps 11 and 12 in accordance with the spacing of said holes 13, thereby affecting the accuracy of the adjustment.

The stem or member 22, however, is adjustably attached to the fitting 14 for lengthwise movements relatively thereto for adjusting the frame 18 towards and from the fitting 14, thus changing the relation of the strips 11 and 12 independently of and without disturbing the previously made connection between the strap 12 and frame 18. For this purpose the stem is threaded, as shown, the threaded portion being received in a correspondingly threaded recess 26 formed in the fitting 14. By turning the stem about its longitudinal axis it can be retracted into or projected outwardly relatively to the fitting 14, and the frame 18 and its attached strap or part 12 moved towards or from the end of the other strap 11. The hole 23 in the frame 18 is preferably large enough to permit the stem to turn freely therein while the frame is held from turning by the strap 12. The size of the hole 23 also permits the frame 18 to swing to a limited extent on the stem 22, as shown in Fig. 5 to allow the strap or part 12 to be easily inserted or removed.

As shown in Figs. 2 and 4, the prong 25 extends in a somewhat angular relation to the axis of the stem 22, in a manner to lie in a plane substantially parallel with the sides of the frame 18. By this construction the prong, after the stem has been adjusted, will lie against the cross bar 19 of said frame in a manner to prevent the stem from accidentally turning and thus placing the buckle out of adjustment.

If desired, the fitting 14 can be provided with a pivoted or otherwise attached loop 29 for the reception of the free end of the strap 12.

Obviously, for some uses, the buckle can be provided with the longitudinally adjustable stem or member having the strap 12 attached directly thereto or to a rigid loop or frame thereon, or, as an alternative, the frame may be swivelled on a fixed projection or part on the strap 11. This latter feature is shown in Fig. 6, wherein 30 represents a member or fitting secured to a suitable part 31, said member having a projection 32 thereon, upon which is swivelled a frame or loop 33 to which a strap or part 34 is secured. This arrangement permits the strap 34 to lie in planes at an angle to the part 31, thus providing a buckle adapted for use on harness or the like.

By the use of the adjustable buckle, one of the straps or other parts to be adjusted is placed in approximately the required relation to the other part by passing said strap or part through the frame 18 and inserting the prong 25 in the nearest hole 13 that will permit such approximate adjustment. Then by merely rotating the stem 22 the required

amount, an additional fine adjustment can be easily and quickly made.

Another desirable form of the adjustable buckle is shown in Fig. 7. This buckle comprises a fitting or member 40 substantially like the fitting 15 of Figs. 1-5, attached to the end of a strap or other member 41. The member also has a pivoted loop 42. Operatively engaging in and having lengthwise movements relatively to the fitting 40 is a threaded adjusting member or stem 43, the free end portion of which, instead of having a frame attached thereto, is provided with a fixed lateral projection 44 terminating in a head or enlargement 45. This projection is adapted to engage in one of a series of holes 46 in a strap or other part 47 for adjustable connection to the strap 41. The holes 46 have enlarged portions 48 through which the head 45 can pass, and reduced portions into which the shank of the projection 44 fits, and is retained by said head. By passing the end of the strap through the loop 42 after the projection has been placed in the desired hole 46, the strap 47 is held in place, as long as a pull is exerted in opposite directions on said straps. When it is desired to make a fine adjustment between said straps, the strap 47 is bent as shown in broken lines, without disconnecting the adjusting member therefrom, thus leaving the projection 44 free for rotation for effecting the required lengthwise movement of the stem.

Claims:—

1. A buckle for connecting two spaced parts, comprising a fitting attached to one of said parts, a frame to which the other part may be detachably secured, and a member extending from said fitting and on which said frame is rotatably connected to turn transversely about the same to permit said part secured thereto to turn in a like manner relatively to said other part.

2. A buckle for connecting two spaced parts, one of which is provided with a row of spaced apertures, a fitting attached to said other part, a frame through which said apertured part passes, a member extending from said fitting and on which said frame is swivelled to permit said apertured part to turn relatively to said other part, and said member having a tongue extending into one of said apertures in said apertured part to hold the same in fixed relation to said frame.

3. An adjustable buckle for connecting two spaced parts, comprising a fitting attached to one of said parts, a member on said fitting extending towards said other part, and a frame swivelled on said member and to which said other part is secured, said member being adjustably secured on said fitting so as to permit said frame to be shifted towards and from said fitting to vary the distance between said spaced parts.

4. An adjustable buckle for connecting

two spaced parts, comprising a fitting attached to one of said parts, a stem on said fitting extending lengthwise towards said other part, and a frame swivelled on said stem and to which said other part is secured, said stem being adjustably mounted on said fitting to move relatively thereto in the direction of the length of said stem, whereby said frame can be adjusted towards and from said fitting to vary the distance between said spaced parts by approximate adjustments of said stem.

5. An adjustable buckle for connecting two spaced parts, comprising a fitting attached to one of said parts, a stem on said fitting extending lengthwise towards said other part, and a frame swivelled on said stem and to which said other part is secured, said stem being threaded in a lengthwise direction and engaging in a threaded hole in said fitting, whereby, by turning said stem in one direction or another, said frame can be adjusted towards and from said fitting to vary the distance between said spaced parts.

25. 6. An adjustable buckle for connecting two spaced parts, comprising a fitting attached to one of said parts, a stem on said fitting extending lengthwise towards said other part, a frame swivelled on said stem, said last mentioned part having a series of spaced holes, and a tongue on said stem engageable in any one of said holes for connecting said part to said frame and affording an approximate adjustment between said parts, said stem being adjustably mounted on said fitting to move relatively thereto in the direction of the length of said stem, whereby said frame can be adjusted towards and from said fitting to provide a secondary adjustment between said spaced parts.

40. 7. An adjustable buckle for connecting two strips of material, one of which is provided with a longitudinal row of spaced apertures, a fitting attached to one of said strips, a stem on said fitting extending towards said other strip, a frame swivelled on said stem, a tongue on said stem extending into any one of said apertures in said apertured strip to adjust the latter relatively to said other strip and hold the same in fixed relation to said frame, and a loop attached to said fitting for the reception of the free end of said apertured strip.

8. An adjustable buckle for connecting two spaced parts, comprising a fitting attached to one of said parts, a stem on said fitting extending lengthwise towards said other part and to which said other part is secured, said stem being adjustably mounted on said fitting to move relatively thereto in the direction of the length of said stem, whereby said second part can be shifted towards and from said first part by appropriate adjustments of said stem.

55. 9. An adjustable buckle for connecting two spaced parts, comprising a fitting attached to one of said parts, a stem on said fitting extending lengthwise towards said other part, and a frame swivelled on said stem and to which said other part is secured, said stem having a screw-threaded connection with said frame to move in the direction of the length of said stem, whereby said frame can be adjusted towards and from said fitting to vary the distance between said spaced parts by appropriate adjustments of said stem, and a part on said stem engageable with said frame to prevent said stem from turning accidentally out of adjustment.

70. 10. An adjustable buckle for connecting two spaced parts, comprising a member mounted on one of said parts and having a screw threaded connection therewith, a frame carried by said member and to which the other part to be connected is detachably secured by means permitting its attachment thereto at different points, and said frame and its attached part being adjustable towards and from said other part by turning said threaded stem relatively to said first part.

75. 11. An adjustable buckle for connecting two spaced parts, comprising a fitting attached to one of said parts, a stem on said fitting extending lengthwise towards said other part and which has a screw threaded engagement with said fitting for adjustment relatively thereto in the direction of the length of said stem, and means on said stem for connecting said stem in any one of a series of spaced holes in the other of said spaced parts, said means permitting said stem to be rotated to effect said adjustment thereof without disconnecting said stem from said part.
